(57) **CLAIM**

The ornamental design for a dead blow hammer, as shown and described.

DESCRIPTION

FIG. 1 is a first perspective view of a dead blow hammer; FIG. 2 is a second perspective view of the dead blow hammer of FIG. 1;

FIG. 3 is a front view of the dead blow hammer of FIG. 1; FIG. 4 is a first side view of the dead blow hammer of FIG. 1;

FIG. 5 is a second side view of the dead blow hammer of FIG. 1;

FIG. 6 is a back view of the dead blow hammer of FIG. 1; FIG. 7 is a top view of the dead blow hammer of FIG. 1; and, FIG. 8 is a bottom view of the dead blow hammer of FIG. 1.

The broken lines illustrate portions of the dead blow hammer that form no part of claimed design.

1 Claim, 5 Drawing Sheets
